UNITED STATES PATENT OFFICE.

HENRICK J. HJORTH, OF WOBURN, MASSACHUSETTS.

T-REST FOR LATHES.

1,127,890.

Specification of Letters Patent.

Patented Feb. 9, 1915.

Application filed May 31, 1913. Serial No. 771,081.

To all whom it may concern:

Be it known that I, HENRICK J. HJORTH, a citizen of the United States, residing at Woburn, in the county of Middlesex and 5 State of Massachusetts, have invented certain new and useful Improvements in T-Rests for Lathes, of which the following is a specification.

The present invention relates to an improvement in T-rests for bench lathes having for its primary object to locate the clamp which secures the rest in such a position that it will not interfere with the hand or tool of the operator in any position of 15 the rest.

Another object is to provide an improved mode of mounting the post or holder for the T-rest so that it may be swung forwardly and downwardly out of the way.

20 The preferred manner in which these and other objects of my invention are carried into effect is illustrated in the accompanying drawings, wherein,

Figure 1 represents a partial elevation 25 of a bench lathe having applied thereto a T-rest made in accordance with my invention and exemplifying the preferred form thereof. Fig. 2 is a longitudinal section of the rest on an enlarged scale, showing also 30 in dotted lines the position of the rest when swung downwardly out of the way. Fig. 3 is an elevation of the rest as seen from the right of Fig. 2. Fig. 4 is a plan view of the slide and holder on which the rest is mounted. Fig. 5 is an elevation in detail of the 35 post on which the rest is mounted and the lock for retaining such post in an upright position.

The same reference characters indicate 40 the same parts in all the figures.

The rest which forms the subject of the present invention is designed to be used in the manner usual with devices of this sort in connection with a small lathe for guiding a hand tool, and as the rest itself and the devices with which it is directly engaged and by which it is held, form the sole subject of the invention, I have not shown, except conventionally, the lathe to 45 which the rest is applied, or the mode of mounting the rest on the bed or ways of the lathe. As to the latter, it is sufficient to say that in Fig. 1 the head stock of a lathe is represented by 1; the tail stock by 2, the bed by 3 and a carriage or block on which the 50 T-rest is mounted by 4. The rest itself is mounted upon a slide 5 which has an under-

cut groove 6 in its under side to receive the head of a stud by which it is clamped in place. Rising from the slide is a post 7 on 60 which the rest 8 is mounted.

The manner of mounting the rest is the first novel feature of the invention. All T-rests of which I have knowledge made prior to my invention have been provided 65 with a shank which is inserted and held in a tubular socket, such socket being split so that the shank of the rest may be adjusted vertically, and having a clamp for closing the socket upon the shank and so securing 70 the rest in its various adjustments. This mode of fastening the rest has been objectionable because of the fact that the clamp interferes with the hand of the workman, or with the tool which he holds when the 75 rest is at the lowest of its adjustments. The primary object of the present invention is to avoid this result by making the rest of such a character that the clamp is always 80 at a sufficient distance below its guiding edge as not to interfere with the operator's hands or the tool, whatever may be the position of the rest. Accordingly I provide as the element which directly engages and holds the rest, a post 7, while the rest itself 85 is provided with a sleeve portion 9 surrounding and embracing the post. This sleeve is slotted or split at 10 and has at or near its lower end lugs 11, 12 through which passes a clamping screw 13. The clamping 90 screw is threaded into one of the lugs and passes freely through the other, having a collar 14 which bears on said other lug. It is provided with an offset handle 15 by which it may be turned to secure the rest. 95

The amount of vertical adjustment permitted to the rest is limited by the amount of penetration of the post 7 in the sleeve 10 and may be as great as the range of adjustment of the old type of T-rest. However, 100 since the clamp, with its offset handle and projecting lugs, is at the lower end of the sleeve 10, which sleeve is integral with or otherwise permanently united to the rest, the projecting parts of the clamp are at a uniform 105 distance from the guiding edge 16 of the rest, so that no matter whether the rest is at the highest point of its adjustment, or at the lowest point, the clamp is always so far below the guiding edge as not to interfere with the tool or the workman's hand.

The rest is also mounted so that it may swing away from the work, and for that purpose is pivoted on an axis parallel to and

below that of the work. The post 7 has a lug 17 lying between two lugs 18 on the front end of the slide 5 and pivotally retained by a pin 19. Thus the post and 5 with it the rest may be placed in the operative position shown in Figs. 1, 2 and 3, or it may be swung to an inoperative position indicated by the dotted lines in Fig. 2. For holding the post and rest in the 10 upright operative position, I provide locking devices consisting of a block 20 secured to the slide 5 and a ring 21 mounted upon the post. The block has a tongue or finger 22 projecting toward the post, and the ring 15 is partly cut away so as to leave a flange 23 shown best in Fig. 5, which is movable to underlie the finger 22. The ring is still further cut away at the end of the flange 23 to provide a clearance space 24 through which 20 the finger 22 passes when the post is brought into or out of position for locking.

The ring is mounted upon the post in a manner which permits it to turn freely through a limited angle, but positively prevents its displacement longitudinally of the 25 post. For thus holding the ring I provide a flange 25, preferably formed integral with the post, on which the ring rests, and a collar or sleeve 26 surrounding the post and having a flange 27 overlying the ring to a greater or less extent. This collar 26 is secured in a sufficiently firm manner to the post as by having a driving fit thereon, and it may be additionally secured 30 by a set screw 28. This set screw passes through the ring and collar and bears against the post. It also serves as a stop for limiting the amount of angular movement of the ring, since it may be given such 35 a length as to project to some extent through a slot 29 in the ring, as shown in Fig. 5. The ends of this slot, by striking the set screw, arrest the movement thereof in either direction, as will be readily seen.

40 When the rest is to be brought from the inoperative to the operative position, the ring is so placed that the clearance space 24 is opposite to finger 22, since, when the ring is in this position, the rest can be brought into upright position without interference with the locking finger. After being brought into such position, the movement in this direction being limited by the flange 25 coming into contact with the 45 surface of the slide 5, the ring 21 is turned slightly to the right, whereupon the lip or flange 23 is brought under the finger 22 and the rest is secured upright.

I claim—

60 1. The combination of a T-rest having a

longitudinally split sleeve in permanent connection therewith, a post surrounded by said sleeve and with respect to which the rest and sleeve are vertically adjustable, and a clamp mounted upon the lower end of the 65 sleeve for binding the same upon the post.

2. In a lathe, a tool rest, a holder therefor with respect to which the rest is vertically adjustable, and a clamping device for securing the rest in any position upon the holder, 70 said clamping device being at the same distance below the guiding edge of the rest in all positions of the latter.

3. In a lathe, a tool rest having a guiding edge, an upright post for supporting the 75 rest, a sleeve surrounding the post, upon the upper end of which sleeve the rest is permanently secured, said sleeve being movable telescopically along the post so as to adjust the height of the rest, and a clamp secured 80 upon the lower end of the sleeve for locking the same in various positions upon the post, and being thereby sufficiently far below the guiding edge of the rest to be clear of the tool and hand of the workman when the rest 85 is lowered as well as when it is raised.

4. In a lathe, a tool rest, a holder for the rest, a slide to which said holder is pivoted in a manner permitting movement of the holder and rest away from the work, and 90 complementary locking devices mounted on the holder and slide respectively for securing the holder and rest in their operative position nearest to the work.

5. In combination with a lathe and a tool 95 rest pivotally mounted so that it may swing toward and from the work, a means for locking the rest in its operative position, comprising a stationary locking tongue and a ring carried with the rest and movable laterally, said ring having a flange or rib adapted to pass under the tongue and by engagement therewith to secure the rest in its 100 operative position.

6. In combination with a lathe, a tool 105 rest slide, a tool rest-holder pivotally connected to said slide, a tool rest secured to said holder, and means for locking the holder and rest in upright position, comprising a block secured to the slide and 110 having a tongue projecting toward the holder, and a ring rotatably mounted upon the holder and having a flange adapted to underlie said tongue.

In testimony whereof I have affixed my 115 signature, in presence of two witnesses.

HENRICK J. HJORTH.
